UNITED STATES PATENT OFFICE.

JOHN E. BAKER, OF RALEIGH, NORTH CAROLINA, ASSIGNOR TO CLINTON CAM COMPANY, OF CLINTON, SOUTH CAROLINA, A CORPORATION OF SOUTH CAROLINA.

LOOM-CAM.

1,189,776.

Specification of Letters Patent.

Patented July 4, 1916.

Application filed February 26, 1916. Serial No. 80,637.

To all whom it may concern:

Be it known that I, JOHN E. BAKER, a citizen of the United States of America, and a resident of Raleigh, county of Wake, 5 State of North Carolina, have invented certain new and useful Improvements in Loom-Cams, of which the following is a full and clear specification.

The object of this invention is to provide 10 a simple expedient for repairing a well known type of loom cam when the periphery thereof becomes so worn that it would have to be removed and replaced by a new cam. My device avoids the waste of time and 15 labor as well as of metal that would occur when necessary to remove and junk the worn cam.

In the drawing Figures 1 and 2 are side elevations of opposite sides of the well 20 known type of Crompton and Knowles loom cam provided with my device; Fig. 3 is a cross-sectional view of a cam taken on the line 3—3 of Fig. 1; and Fig. 4 is a detail perspective view of the patch removed.

25 In the drawing annexed, *a* designates the body of the usual picker cam now in extensive use on the well known Crompton and Knowles loom. Bolted to opposite sides of this cam at approximately diametrically opposite points are the usual picker point *b* and the check point of wobble *c*. For the proper positioning and adjustment of these points on the cam, there is usually provided in the cam body *a* a series of four slots *d* through which the bolts *e* for securing the 30 points to the cam are passed, the points being provided with suitable bolt holes or slots positioned so as to coincide with the slots in the cam body.

40 In the operation of the loom, the picker ball wears off the periphery of the cam body, as shown in the drawing at *f*, at points between the cam points *b* and *c*. It is now the general practice to remove the 45 points *b* and *c* and junk the cam body. With my device I avoid this waste by bolt- 50 ing to the side of the cam body an approxi- mately semi-circular plate *g*, this plate being bolted to the same side of the cam body 55 that the picker point *b* is bolted to. This patch plate *g* is sufficiently long to have its end abut against the ends of the picker point so that the picker point is braced or backed up by this patch plate. The 60 patch plate is provided with arcuate slots

h so positioned that when the patch plate is in position the slots coincide with the slots in the cam body, so that this patch plate may be bolted to the cam body by the same bolt that secures check point *c* 60 to the cam body, and an additional bolt *i* may be employed. The corresponding slots in the picker point, the patch plate and the cam body enable the picker point, and the patch plate to be adjusted circumferentially 65 on the cam body sufficiently to always have at least one end of the patch plate abut against the picker point *b* to form an abutment therefor and thus assist in holding it 70 in proper position.

It will be observed that the shape of the patch plate is such that when secured in position it bridges both of the worn places in the cam and thus provides a bearing surface for the picker ball or roll. To further insure the cam patch being held rigidly in place on the cam body, I provide in the inner surface of the same a groove which fits over the usual annular rib *j* formed on the 75 side of the cam body *a*.

Having thus described my invention, what I claim is:

1. A loom cam consisting of a body part provided with a series of slots, a picker point and a check point and bolts for securing these points to the body of the cam, and a patch plate approximately semi-circular in shape and provided with slots, this plate being fastened to the cam body by the same bolt that fastens the check point and having one end abutting against the adjacent end of the picker point.

2. A loom cam consisting of a body part provided with a series of slots, a picker point and a check point and bolts for securing these points to the body of the cam, and a patch plate approximately semi-circular in shape and provided with slots, this plate being fastened to the cam body by the same bolt that fastens the check point and having one end abutting against the adjacent end of the picker point, the cam body being provided with an annular rib and the patch plate being provided with a similar groove 100 in its inner face to receive said rib.

3. A loom cam body provided with a picker point secured to one face thereof, and a semi-circular patch plate having a circumference corresponding to the circumference of the cam body and provided with a 110

slot, a bolt for fastening this patch plate to the cam body, said bolt passing through said slot, said bolt and slot connection permitting the cam patch to be rotatively adjusted 5 to cause it to abut against one end of the picker point.

4. The combination with a loom cam, of a patch plate attached to one side thereof, and means whereby this plate is rendered circumferentially adjustable. 10

5. The combination with a loom cam having a picker point projecting laterally from the face of the cam, of a patch plate, and means for fastening it against the side of the cam in abutting relation to the projecting part of the point. 15

In testimony whereof I hereunto affix my signature.

JOHN E. BAKER.
